UNITED STATES PATENT OFFICE.

CHARLES HAMMER, OF QUEENS, NEW YORK, ASSIGNOR TO AMERICAN METAL CAP COMPANY, OF BROOKLYN, NEW YORK, A CORPORATION OF NEW YORK.

BAND-LUG CLOSURE.

Application filed January 19, 1922. Serial No. 530,267.

To all whom it may concern:

Be it known that I, CHARLES HAMMER, a citizen of the United States, and a resident of Queens, in the county of Queens and State of New York, have invented certain new and useful Improvements in Band-Lug Closures, of which the following is a specification.

This invention relates to closures for glass containers, the object thereof being to provide an improved combined removable sealing band and a rotatable and reusable closure.

One of the objects of the invention is the provision of a shallow flanged cap having a strengthened rolled or beaded edge provided with inwardly extending locking projections formed from such beaded edge and adapted to engage the projections or threads of a glass container, and a removable sealing band cooperating with the cap in such way as to materially extend below the flange thereof and engage directly with a shoulder of the container whereby the cap is secured on the container and the package effectively sealed, yet when the sealing band is removed the cap is reusable on the rotation thereof to seal the container during the further use of the contents thereof.

Another object of the invention is the provision of an improved combined removable sealing band and a rotatable and reusable closure having a strengthened rolled or beaded edge provided with inwardly extending locking projections, in which the band and the flange of the cap are of substantially the same depth and in which the band directly engages the rolled edge of the cap and the under wall of a shoulder of the container for sealing the cap on to the container when the cap is first applied thereto, and in which the container is provided with a special form of multiple threads or projections and a shoulder spaced at such distance therefrom that the cap and the band can be sealed under considerable downward pressure without the cap projections engaging such shoulder.

In the accompanying drawing illustrating one embodiment of my invention, Fig. 1 is a plan view partially broken away.

Fig. 2 is a partial vertical section of the cap and band before sealing.

Fig. 3 is a partial section showing the sealed package.

Fig. 4 shows the use of the cap after the sealed package has been opened.

Fig. 5 is a partial view looking inwardly on the flange of the cap to show the lug.

This improved closure comprises a metal cap 2 and a sealing band 3 particularly applicable to a glass container, such as a jar 4. The cap 2 comprises a top having a shallow flange or skirt 5 provided with a lower strengthened edge in the form of a bead or rolled edge 6, preferably obtained by rolling the lower edge of the flange upwardly and outwardly, so as to conceal the raw edge of the flange and render it more sanitary as well as prevent injury to the hand of the user. This beaded or rolled edge is provided at intervals with inwardly extending locking projections 7 (see Fig. 5) of which four are shown and in the present instance these projections are formed directly from the rolled edge, preferably by shaping or deforming such rolled edge, as for instance by flattening the same to project the projections radially inward a sufficient distance to engage the projections or threads of the container.

The container or jar 4 is provided with four projections or threads 8 on its neck of special formation, that is to say, the projections or threads of the glass container comprise a single row of projections having their ends spaced apart. Each of the projections has a relatively inclined edge terminating at an end 9 in a relatively sharp inclined portion. The container is also provided with a rib or shoulder 10 spaced below the lowermost portion of each thread 8, sufficient to permit the lugs 7 that engage the lower faces of the container threads, to pass along without being brought into engagement with the rib 10. As stated, the end portions 9 of the container threads are preferably tapered and the adjacent ends of the threads are separated or spaced apart to permit the applying of the cap with the lugs passing downwardly between these ends, without the usual turning movement required where the threads overlap.

The closure is further provided with a band 3 with its upper edge 13 bent inwardly to form a small flange. The band may have a tongue 15 at the ends that overlaps the other end of the band, with a second tongue 16 projecting through a slot in the other tongue to hold the bands together so as to

permit the loosening of the band by simply bending out these tongues. It will be further observed that the rib 10 projects outwardly a greater distance than the projections 8 on the jar neck, and the band 3 is of a size to pass down in engagement with the outer wall of the rib 10, see Fig. 2.

In the application of the closure to the jar, the cap 2, preferably with a liner disk 12, is placed on the jar with the lugs passing downwardly between the ends of the threads 8, thus permitting the cap to seat on the jar. It is not necessary at this time to bring the lugs 7 into binding engagement 15 with the threads 8. Thereupon, the band 3 is passed downwardly over the cap and over the rib 10 of the jar until its flange 13 engages the bead 6 on the cap, as indicated in Fig. 2. This will cause the band 3 to project downwardly at its lower portion a short distance below the rib 10, see Fig. 2, and the lower portion 14 of the band is thereupon bent inwardly against the lower wall of the rib 10, as shown in Fig. 3. Preferably 20 considerable downward pressure is brought to bear on the top of the cap, or on the top of the flange 13 of the band, or at both of these places, and this pressure is maintained while the band edge 14 is bent inwardly against the bottom of the rib 10. During this operation, it will be understood 25 that the lugs 7 can move downwardly away from the threads 8 on the jar neck, because of the free space between these threads and 30 the rib 10.

When it is desired to open the container, the band tongues are bent and the band easily removed. This will free the cap for removal. Where only part of the jar contents are removed, the cap can be replaced a number of times, and these lugs 7 will engage the threads 8 on the jar to furnish a very tight seal by merely screwing it down, yet permit easy removal. While the lugs 7 45 as shown are formed by flattening of the bead 6, it is to be understood that any form of lug on the flange can be employed, in combination with a beaded edge adapted to be engaged by the sealing band.

50 From the foregoing it will be seen that the skirt or flange of the cap is of just sufficient height or depth to overlap the threads of the glass container, so that the cap can be made with a shallow flange or 55 skirt, while the sealing band is of such depth or height that it will have its upper inturned edge engaging or overlapping the strengthened or rolled edge of the cap and extend beyond the lower edge of the cap to 60 overlap the shoulder or rib of the glass container sufficiently to permit its lower edge to be bent under such shoulder. And that furthermore, the shallow flange is of just sufficient depth to enable its lugs to pass 65 under the glass threads of the container

and effectively pass therebetween and the shoulder of such container, which latter projects sufficiently beyond the glass threads to enable the overlapping sealing band to engage the same on its outer wall, and to be bent directly under such shoulder in an effective manner to hold the cap in place.

Furthermore, by reason of the space between the ends of the glass threads the cap can be efficiently pressed down without turning it when the sealing band is applied, and this effective sealing is also obtained even though the cap may be somewhat turned by reason of the sharp inclination at the ends of the threads, since the effective drawing down of the cap is largely obtained by the long gradual inclination at the underside of the glass threads.

Thus by this construction, I am able to provide a combined shallow flanged rotatable cap having a strengthened or beaded edge provided with locking lugs and capable of ready reuse and a sealing band cooperating with such strengthened edge and the container shoulder itself thereby to hold the cap on the container and seal the same.

And I believe that I am the first to provide a combined shallow flanged cap and sealing band in which the band and the cap are of substantially the same depth and in which the cap is provided with a strengthened or rolled edge having locking lugs, so that it is a rotatable and reusable cap when the sealing band is removed.

And I also believe that I am the first to provide a shallow flanged cap having a strengthened or rolled edge with locking lugs or projections extending inwardly from such strengthened edge in combination with a sealing band, wherein the structure of the cap and the glass threads is such that vertical movement of the cap projections in one direction during the operation of sealing the band under the shoulder is permitted. The use of this improved cap permits the user to readily determine whether the cap has been tampered with at any time prior to the removal of the sealing band.

It is to be understood that by describing in detail herein any particular form, structure or arrangement, it is not intended to limit the invention beyond the several terms or the requirements of the prior art.

What I claim is:

1. A combined rotatable and reusable metal cap and sealing band, said cap comprising a top having a depending skirt provided with a strengthened, curled or beaded lower edge, and inwardly extending locking projections, said sealing band extending below said skirt and having its top and bottom portions bent inwardly, the former to directly engage the strengthened edge of the cap and the latter to engage under the shoulder of the container, the sealing band

and cap so cooperating that the sealing band forms the first locking means for the cap without the rotation thereof while the projections of the cap form the second locking means on the removal of the band.

2. A combined rotatable and reusable metal cap and sealing band, said cap comprising a top having a depending shallow skirt provided with a strengthened, curled or beaded lower edge, and inwardly extending locking projections formed from said strengthened edge, said sealing band extending below said skirt and having its top and bottom portions bent inwardly, the former to directly engage the strengthened edge of the cap and the latter to engage under a shoulder of the container, the sealing band and cap so cooperating that the sealing band forms the first locking means for the cap without the rotation thereof while the projections of the cap form the second locking means on the removal of the band.

3. A combined rotatable and reusable metal cap and sealing band, said cap comprising a top having a depending skirt provided with a strengthened, curled or beaded lower edge, and inwardly extending locking projections, said sealing band having substantially the same depth as the skirt and extending below said skirt and having its top and bottom portions bent inwardly, the former to directly engage the strengthened edge of the cap and the latter to engage under a shoulder of the container, the sealing band and cap so cooperating that the sealing band forms the first locking means for the cap without the rotation thereof while the projections of the cap form the second locking means on the removal of the band.

4. A combined rotatable and reusable metal cap and sealing band, said cap comprising a top having a depending shallow skirt provided with a strengthened, curled or beaded lower edge, and inwardly extending locking projections formed from said strengthened edge, said sealing band having substantially the same depth as the skirt and extending below said skirt and having its top and bottom portions bent inwardly, the former to directly engage the strengthened edge of the cap and the latter to engage under a shoulder of the container, the sealing band and cap so cooperating that the sealing band forms the first locking means for the cap without the rotation thereof while the projections of the cap form the second locking means on the removal of the band.

5. A combined rotatable and reusable metal cap and sealing band, said cap comprising a top and a depending skirt having an outwardly extending reinforcing portion and inwardly extending relatively short spaced locking projections, said sealing band having a pair of locking portions, one coop-

erating with the outwardly extending reinforcing portion of the cap and the other with a shoulder of a container, said sealing band and cap so cooperating that the sealing band forms the first locking means for the cap without the rotation thereof while the projections of the cap form the second locking means on the removal of the cap.

6. A combined rotatable and reusable metal cap and sealing band, said cap comprising a top and a depending shallow skirt having an outwardly extending reinforcing portion and inwardly extending relatively short spaced locking projections, said sealing band having a pair of locking portions, one cooperating with the outwardly extending reinforcing portion of the cap and the other with a shoulder of a container, said sealing band and cap skirt having substantially the same depth and so cooperating that the sealing band forms the first locking means for the cap without the rotation thereof while the projections of the cap form the second locking means on the removal of the cap.

7. A sealed package comprising a container having a single row of projections or threads with the ends spaced apart and a shoulder spaced below said threads, a rotatable and reusable metal cap comprising a top having a depending skirt provided with a strengthened, curled or beaded lower edge and with inwardly extending locking projections, each of a length adapted to pass between the spaced ends of a pair of threads of the container, and a removable sealing band overlapping the strengthened edge and underlapping the shoulder, said sealing band and cap so cooperating that the sealing band forms the first locking means for the cap without the rotation thereof while the projections of the cap form the second locking means on the removal of the band, the structure of the threads and cap projections also so cooperating as to permit vertical movement of the cap projections in the direction of the depth of the cap during the operation of sealing the band under the shoulder.

8. A sealed package comprising a container having a single row of projections or threads with the ends spaced apart, and a shoulder spaced below said threads, each of said threads having an inclined lower edge and a tapered upper end, the space between said tapered end and the shoulder being greater than that between the major part of the lower edge of the thread and said shoulder, a rotatable and reusable metal cap comprising a top having a depending shallow skirt provided with a strengthened, curled or beaded lower edge and with inwardly extending locking projections formed from such strengthened edge, each of a length adapted to pass between the spaced ends of a pair of threads of the container, and a re-

movable sealing band overlapping the band, the structure of the threads and cap projections also so cooperating as to permit vertical movement of the cap projections in the direction of the depth of the cap during the operation of sealing the band under the shoulder. 10
